UNITED STATES PATENT OFFICE.

ANDREW SYROCKI, OF DETROIT, MICHIGAN.

DESIGN FOR A COMBINATION FLOOR LAMP AND CLOTHESRACK.

Application filed February 20, 1925. Serial No. 12,443. Term of patent 3½ years.

To all whom it may concern:

Be it known that I, ANDREW SYROCKI, a citizen of the United States, residing at the city of Detroit, in the county of Wayne and State of Michigan, have invented a new, original, and ornamental Design for Combination Floor Lamp and Clothesrack, of which the following is a specification, reference being had to the accompanying drawing, forming part thereof.

The figure is a perspective view of a combination floor lamp and clothesrack showing my new design.

I claim:

The ornamental design for a combination floor lamp and clothesrack, as shown.

ANDREW SYROCKI.
